POWER LIFT FOR TRACTORS

Edward A. Johnston, Chicago, Ill., assignor to
 International Harvester Company, a corpora-
 tion of New Jersey

Application May 22, 1935, Serial No. 22,890

16 Claims.

(Cl. 97—50)

The present invention relates generally to farm tractors for propelling, carrying, and operating agricultural implements, and more specifically to power operated lifting devices.

5 The fundamental object of the invention is to provide improved mechanism mounted on the tractor and driven by power derived from the engine for lifting, lowering or otherwise adjusting implements, such as plows and cultivators, attached to or operated by the tractor.

10 More specifically, one object of the invention is to provide a power lift mechanism which is hydraulically actuated. Another object subsidiary to said object is to provide an improved and simplified two-way acting hydraulic mechanism.

15 Another object is to provide a hydraulic mechanism which may be constructed to move an operating lifting shaft through substantially more than a half revolution, whereby the crank may be connected to lifting members to move past dead center in either of two positions.

20 Another object is to provide a hydraulic lifting mechanism particularly adapted to the oscillation of a crank of rockshaft for use in lifting implements.

25 The above objects and others, which will be apparent from the detailed description to follow, are accomplished by the mounting of a hydraulic mechanism of a narrow piston type, the piston being mounted in a cylinder for reciprocation by the application of pressure at either end of the piston. The lifting member in the form of a rockshaft is connected to and moved by the piston by means of a rack formed on the piston and 30 a gear carried by the shaft. A hydraulic pump is mounted on the tractor in any suitable position for supplying operating liquid under pressure to the hydraulic mechanism. A suitable control valve and properly located conduits are provided 35 for delivering the high pressure liquid to either end of the piston and for allowing the escape of liquid simultaneously from the other end of the piston. In order to provide a mechanism in which the supply of high pressure liquid is rendered ineffective after the piston has completed its stroke, valve means are utilized, which are automatically operable by movement of the piston into its respective positions of rest at the end of its strokes in each direction.

40 In the drawings:

Figure 1 is a plan view of the rear portion of a conventional tractor, on which a power lift incorporating the invention is mounted;

45 Figure 2 is a side elevation of the same structure shown in Figure 1 with one axle housing

broken away to better show the power lift mechanism;

5 Figure 3 is a plan view of the power lift casing with the valve housing broken away upon a horizontal section, to illustrate the operation of the valve;

Figure 4 is a transverse vertical section taken on the line 4—4 of Figure 3;

10 Figure 5 is a horizontal section taken on the line 5—5 of Figure 6;

Figure 6 is a longitudinal vertical section taken on the line 6—6 of Figure 3; and,

15 Figure 7 is a transverse vertical section taken on the line 7—7 of Figure 1, showing only the power lift mechanism.

20 Only the rear portion of a tractor has been shown as the power lift mechanism incorporating the invention may be used on any of the conventional types of farm tractors. The tractor illustrated has a frame 10 connected to a transversely 25 extended rear axle housing 11. Depending housings 12 at the end of the housing 11 contain the driving mechanism for traction wheels 13. The rear portion of an engine 14 is shown mounted on the frame 10. The transmission casing 15 at the 30 rear of the frame 10 is spaced a substantial distance rearwardly from the rear end of the engine 14. A gasoline tank 15' is mounted above the frame between the transmission casing and the engine, being supported in position by upstanding 35 brackets 10'. A substantial space remains between the tank 15' and the frame 10 and longitudinally between the brackets 10'. It is in this space that the power lift mechanism is mounted.

35 The power lift casing 16 extends in a longitudinal direction with respect to the tractor and is positioned adjacent one side of the frame 10 in the space between the engine and the transmission casing. Said casing is of a cross section, as best shown in Figure 7. Aligned bores 17 are 40 formed at each end of the casing 16 into which a cylinder 18 is fitted, with the ends of the cylinder flush with respect to the ends of the casing.

45 A piston 19 is mounted for reciprocation in the cylinder 18, piston rings 20 being provided at each end of the piston to form liquid seals.

50 As best shown in Figure 7, the interior of the casing 16 is formed intermediate its ends with an inwardly extending boss 21 formed with a bore 22. A transversely extending lifting shaft 23 extends 55 through the bore 22. At the other side of the casing, a housing 24 is secured to the casing over an opening 25. The casing 24 is provided with an extension 26 within the casing 16. A bore 27 formed in the extension 26 is in alignment with 55

length, a past dead center lock may readily be provided for with only slightly more than 180 degrees movement of the lifting cranks.

Although applicant has shown and described a 5 preferred embodiment of his improved hydraulic lift mechanism, it is to be understood that he claims as his invention all modifications falling within the scope of the appended claims.

What is claimed is:

10 1. A power lift device for tractors comprising, in combination with a tractor and an implement to be lifted, a rockshaft mounted on the tractor, lifting connections between the rockshaft and the implement, a power actuated shaft mounted on 15 the tractor, a lifting lever arm connected to said shaft, a lifting member connecting said lever arm and rockshaft, and means for operating the lifting shaft through an angular movement of substantially more than 180 degrees whereby the lever 20 arm may be moved to a past dead-center position in either of its extreme positions.

25 2. A power lift device for tractors comprising, in combination with a tractor and an implement to be lifted, a transverse rockshaft mounted on 30 the tractor at the rear thereof, lifting connections between the rockshaft and the implement, a power actuated shaft mounted on the tractor spaced forwardly from the rockshaft, a lifting lever arm connected to said shaft, a longitudinal 35 lifting member capable of transmitting tension and compression connecting said lever arm and rockshaft, and means for operating the lifting shaft through an angular movement of substantially more than 180 degrees whereby the lever 40 arm may be moved to a past dead-center position in one extreme position with the lifting member under tension and to a past dead-center position in the other position with the lifting member in compression.

45 3. A power lift device for tractors comprising, in combination with a tractor and an implement to be lifted, a transverse rockshaft mounted on 50 the tractor, lifting connections between the rockshaft and the implement, a power actuated shaft mounted transversely on the tractor, a lifting lever arm connected to said shaft, a lever arm on the rockshaft, a lifting member of substantial 55 length with respect to the length of the lever arm connecting said lever arm and lever arm on the rockshaft, whereby movement of said member is substantially rectilinear, and means for operating the lifting shaft through an angular distance of substantially more than 180 degrees whereby the lever arm may be moved to a past dead-center position in either of its extreme positions.

60 4. A power lift device for tractors comprising, in combination with a tractor and an implement to be lifted, a transverse rockshaft mounted on the tractor, lifting connections between the rockshaft and the implement, a power actuated shaft mounted transversely on the tractor, a lifting lever arm connected to said shaft, a lever arm on the rockshaft, a lifting member of substantial 65 length with respect to the length of the lever arm connecting said lever arm and lever arm on the rockshaft, whereby movement of said member is substantially rectilinear, and a two way hydraulic piston operable to rock the lifting shaft through an angular distance of substantially 70 more than 180 degrees whereby the lever arm may be moved to a past dead-center position in either of its extreme positions.

75 5. A power lift device for tractors comprising, in combination with a tractor and an implement to be lifted, a transverse rockshaft mounted on the

tractor, lifting connections between the rockshaft and the implement, a power actuated shaft mounted transversely on the tractor, a lifting lever arm connected to said shaft, a lever arm on the rockshaft, a lifting member capable of transmitting tension and compression of substantial length with respect to the length of the lever arm connecting said lever arm and the lever on the rockshaft whereby movement of said member is substantially rectilinear, and means for operating the lifting shaft through an angular movement of substantially more than 180 degrees whereby the lever arm may be moved to a past dead-center position in one extreme position with the lifting member under tension and to a past dead-center position in the other position with the lifting member under compression.

5 6. A power lift device for tractors comprising, in combination with a tractor and implement connected thereto, a casing mounted on the tractor, a transverse rockshaft extending through said casing, lifting connections between said shaft and the implement, a cylinder formed in said casing, a piston mounted for reciprocation in said cylinder, a rack formed along one side of the piston, a gear 20 mounted on the rockshaft and positioned for engagement with said rack, and means to supply fluid under pressure to the cylinder.

25 7. A power lift device for tractors comprising, in combination with a tractor and implement connected thereto, a casing mounted on the tractor, a transverse rockshaft extending through said casing, lifting connections between said shaft and the implement, a cylinder formed in said casing, a piston mounted for reciprocation in said cylinder, 30 valve means for supplying fluid under pressure to either end of said piston, a rack formed along one side of the piston, a gear mounted on the rockshaft and positioned for engagement with said rack whereby reciprocation of the piston oscillates the 35 rockshaft, and means operated by the tractor engine to supply fluid under pressure to the valve means.

40 8. A power lift device for tractors comprising, in combination with a tractor and implement connected thereto, a casing mounted on the tractor, a transverse rockshaft extending through said casing, lifting connections between said shaft and the implement, a cylinder formed in said casing, a two-way piston mounted for reciprocation in 45 said cylinder, a rack formed along one side of the piston, a gear mounted on the rockshaft and positioned for engagement with said rack, and means to supply fluid under pressure to the cylinder at either end of the piston.

55 9. A power lift device for tractors comprising, in combination with a tractor and implement connected thereto, a casing mounted on the tractor, a transverse lifting shaft extending through said casing, lifting connections between said shaft and the implement, a cylinder formed in said casing, a two-way piston mounted for reciprocation in said cylinder, a rack formed along one side of the piston, a gear mounted on the rockshaft and positioned for engagement with said rack, and means to supply fluid under pressure to the cylinder at either end of the piston, the movement of said piston being a distance sufficient to rock the lifting shaft substantially more than 180 degrees.

60 10. A power lift device for tractors comprising, in combination with a tractor and implement connected thereto, a casing mounted on the tractor, a transverse rockshaft extending through said casing, lifting connections between said shaft and the implement, a cylinder formed in said casing, 70

- a piston mounted for reciprocation in said cylinder, valve means for supplying fluid under pressure to either end of said piston, and for simultaneously draining fluid from the other end, a rack 5 formed along one side of the piston, a gear mounted on the rockshaft in engagement with said rack whereby reciprocation of the piston oscillates the rockshaft, and means operated by the tractor engine to supply fluid under pressure to the valve 10 means.
11. A power lift device for tractors comprising, in combination with a tractor and an implement to be lifted, a transverse rockshaft mounted on the tractor, lifting connections between the rock- 15 shaft and the implement, a lifting crank pivotally mounted on the tractor on a transverse axis spaced longitudinal of the tractor from the rock- shaft, a lifting arm on the rockshaft, a lifting member capable of transmitting tension and com- 20 pression connected, to said arm and the lifting crank, and power operated means for rocking the lifting crank substantially more than 180° in oppo- site angular directions whereby the point of con- 25 nection of the lifting member with the lifting crank may be moved past dead-center position in either direction with respect to the center line of the axis of the crank and the pivot axis of the lifting member on the lifting arm.
12. A power lift device for tractor comprising, 30 in combination with a tractor and an implement to be lifted, a transverse rockshaft mounted on the tractor, lifting connections between the rock- shaft and the implement, a lifting crank pivotally mounted on the tractor on a transverse axis 35 spaced longitudinal of the tractor from the rock- shaft, a lifting arm on the rockshaft, a lifting member capable of transmitting tension and compres- sion connected to said arm and the lifting crank, and a two-way hydraulic device operable 40 to rock the lifting crank substantially more than 180° in opposite angular directions whereby the point of connection of the lifting member with the lifting crank may be moved past dead-center position in either direction with respect to the center line of the axis of the crank and the pivot axis 45 of the lifting member on the lifting arm.
13. A power lift device for tractor comprising in combination with a tractor and an implement to be lifted, a transverse rockshaft mounted on the tractor, lifting connections between the rock- 50 shaft and the implement, a lifting crank pivotally mounted on the tractor on a transverse axis spaced longitudinal of the tractor from the rock- shaft, a lifting arm on the rockshaft, a lifting member capable of transmitting tension and com- 55
- pression connected to said arm and the lifting crank, a casing mounted on the tractor, a lifting shaft extending into the casing, and a two-way hydraulic piston within the casing for rocking said shaft substantially more than 180 degrees 5 in either angular direction, the lifting crank being secured to said shaft in a position whereby the point of connection of the lifting member with the lifting crank may be moved past dead-center position in either direction with respect to the center line of the axis of the crank and the pivot axis of the lifting member on the lifting arm.
14. In a field implement, the combination with a traveling support and a tool carrying member adjustably connected thereto, of a casing mounted on the support, a piston mounted in said casing for oscillation therein, means for delivering fluid under pressure into the casing at either side of the piston and for simultaneously removing fluid from the other side, a lifting shaft mounted on the support, lifting connections between said shaft and the earth working member, and power transmitting connections between said shaft and the piston operable by actuation of the piston to rock the shaft in opposite angular directions substantially more than 180 degrees whereby an over-dead-center lock may be provided in either extreme position.
15. In a field implement the combination with a tool carrying member and a traveling support therefor, of a casing mounted on the support, a piston oscillative in said casing, means for delivering fluid under pressure at a substantially continuous rate to either side of the piston, means operated by movement of the piston for by-passing fluid being supplied to the high pressure side when the piston reaches the end of its stroke in either direction and lifting connections between the piston and the tool carrying member.
16. In a field implement the combination with a tool carrying member and a traveling support therefor, of a casing mounted on the support, a piston oscillative in said casing, means for delivering fluid under pressure at a substantially continuous rate to either side of the piston, means operated by movement of the piston for by-passing fluid being supplied to the high pressure side when the piston reaches the end of its stroke in either direction and lifting connections between the piston and the tool carrying member, said connections including a rockshaft actuated by the piston to move substantially more than 180 degrees in opposite angular directions.
